UNITED STATES PATENT OFFICE

CARROLL E. LEWIS, OF MINNEAPOLIS, MINNESOTA, ASSIGNOR TO LEWIS AIR CONDITIONERS, INC., OF MINNEAPOLIS, MINNESOTA, A CORPORATION OF DELAWARE

AIR CONDITIONING APPARATUS (GRAVITY ACTUATED)

Application filed August 14, 1930. Serial No. 475,177.

This invention relates to air conditioning apparatus and particularly to a device for humidifying, washing and heating the air in dwellings, offices and buildings.

It is an object of my present invention to provide a comparatively simple humidifying device wherein the flow or circulation of air is actuated by gravity rather than a fan or impeller and wherein the circulating air is thoroughly washed and efficiently humidified in its passage through a flue.

A further object is to provide a comparatively inexpensive humidifier of the gravity-actuated type having a high evaporative capacity and operative to prevent discharge of unevaporated particles into the room or building served.

More specifically it is an object of my invention to provide an efficient humidifier and air conditioner wherein a substantially vertical air treating flue is utilized having therein a heating device for raising the evaporative capacity of the air and for heating the air in its passage and having means disposed medially and directed longitudinally of said flue for discharging finely divided particles of moisture within the flue and a deflector associated with said means for causing said particles of moisture to be directed transversely and substantially radially of said means to fill the entire cross section of said flue.

It is a further object, in a device of the class described, to provide means for directing air into the lower portion of the flue in such a manner as to produce a uniform distribution of the air throughout the entire cross section of the flue.

Another object is to provide a device of the class described having associated therewith efficient means for regulating the humidity and temperature of the air treated.

These and other objects and advantages of the invention will be fully set forth in the following description made in connection with the accompanying drawings, in which like reference characters refer to similar parts throughout the several views, and in which:—

Fig. 1 is a view mostly in vertical section

through an embodiment of my invention, portions of the ornamental casing, the flue, heating unit and tempering chamber being broken away;

Fig. 2 is a vertical section taken on the line 2—2 of Fig. 1;

Fig. 3 is a cross section taken on the line 3—3 of Fig. 1;

Fig. 4 is a detail view showing the moisture distributing nozzle in longitudinal section and the distributing deflector associated therewith;

Fig. 5 is a detail perspective view of a portion of the nozzle, and

Fig. 6 is an electrical diagram showing the control circuits.

In the embodiment illustrated in the drawings, my entire apparatus with the exception of the humidity control is conveniently housed in an ornamental rectangular casing C having front, rear and side walls, a closed top and an open bottom. The casing is preferably supported in spaced relation to the floor by means of legs L.

In the medial portion of casing C a substantially vertical air conditioning flue 8 is mounted, said flue having a closed lower end and communicating at its upper end with a flaring cowl or discharge hood 9. Discharge hood 9 may extend across the entire front of casing C. An elongated opening 10 is provided in the upper portion of the front wall of casing C to permit the discharge of the conditioned air and a suitable grating 11 may be disposed across said opening. Declined air intake passages 8a communicate with the lower end of flue 8, as shown, two of said intake passages being provided at opposite sides of the flue. Within said passages a series of declined parallel deflector plates 12 are mounted adapted to divide the entering air, causing the same to pass inwardly into the central portion of the flue and filling the entire cross section thereof.

In the lower portion of flue 8 and disposed centrally thereof some distance above the upper edges of air intake passages 8a is a suitable moisture distributing nozzle 13 directed downwardly, longitudinally of said flue. It is essential to provide a nozzle which

will discharge a finely divided or atomized conical spray and the nozzle as shown comprises a tubular body 13a, the upper end thereof being threaded for connection with a conduit or coupling 14. The lower portion of the nozzle has an enlarged internal passage at the outer end of which a disk 15 is clamped, said disk having a series of spiral passages 15a pressed therein and extending therethrough. Another disk 16 is disposed beneath disk 15, disk 16 having a central discharge port 16a therein through which the moisture is distributed. Disks 16 and 15 may be clamped against the lower end of the nozzle body 13a by means of an annular cap 13b which may have threaded engagement with the exterior of the lower end of body 13a. Conduit or coupling 14 for the nozzle may be supported in horizontal position from one of the walls of flue 8 thereby properly positioning the nozzle medially of and longitudinally of the flue. The clamping cap 13b of my nozzle may support a deflection plate or disk 17, said disk being disposed concentrically of the nozzle and being of slightly greater circumference than the cross sectional area of the conical spray discharged at the plane of intersection with said spray. Supporting rods 17a may connect the cap with the periphery of the disk.

Directly above nozzle 13 and disposed transversely of flue 8 I provide a suitable heating unit, indicated as an entirety by the letter U and which may conveniently be in the form of a tubular radiator having the headers 18 and 19 disposed at opposite sides of the flue, connected by a series of horizontal tubes 20, said tubes carrying transverse and vertically disposed fins 21 for increasing the area of heat transmission surfaces. The header 18 is connected by a short coupling 22 with a suitable tempering chamber 23. Said tempering chamber may comprise a cup-like casing having a removable top 23a secured thereto. The lower end of tempering chamber 23 is connected with a hot water or steam supply conduit 24 which may connect with the supply pipes of a circulating heating system. The header 19 of the heating unit is connected with a return conduit 25 which may be connected with the return pipe of the circulating heating system. Within chamber 23 a tempering coil 26 is centrally disposed, the discharge end thereof being connected by curved conduit 27 with the nozzle coupling or conduit 14. Water under pressure is supplied to the tempering coil and nozzle by means of a water supply pipe 28 which is connected with a suitable filter or strainer 29, the discharge end of said strainer connecting with the intake end of a valve casing 30 having mounted therein, as diagrammed in Fig. 6, a solenoid or electro-magnetically operated valve 30a for controlling the water supply, the discharge end of cas-

ing 30 being connected by a curved conduit 31 with the intake end of tempering coil 26. Electric service wires for supplying the coil of the solenoid valve may extend through a suitable conduit 32 connected with the bottom of valve casing 30.

A thermostatically operated circuit control 33 of the conventional immersion type is supported from the top 23a of the tempering chamber and the well or immersion portion 75 of the device extends within the central part of the chamber substantially concentric with the tempering coil 26.

As clearly shown in Fig. 6, the thermostatically operated circuit control 33 as well as 80 a humidity control 34 are connected in series with the electromagnetic coil of solenoid valve 30a. The humidity control 34 may be of any suitable type wherein an element responsive to variations in the humidity of air to which it is subjected controls the opening and closing of an electrical circuit. The solenoid valve is so constructed that when its magnetic coil is energized the valve will be opened permitting passage of water through the tempering coil and into nozzle 13. Obviously the solenoid valve will not be opened unless circuits to both tempering control 33 and humidity control 34 are closed. At the bottom of flue 8 an inverted pan-shaped sound absorbing screen 35 is mounted, said screen covering a substantial portion of the bottom, being centrally disposed thereof. Below screen 35 a drain pipe 36 communicates with the bottom of the flue for removing any accumulation of water.

Operation

In operation a substantial draft of air will flow upwardly through flue 8 due to the effect 105 of gravity and the heat supplied by heating unit U. It will be noticed that this air must enter the bottom of the flue through the intake passages 8a, being divided by the several deflector plates 12 which causes the air to 110 enter in downwardly directed streams, the air being uniformly distributed throughout the cross sectional area of the lower portion of flue 8.

No moisture will be discharged from nozzle 115 13 until the steam, water or other circulating heating fluid in tempering chamber 23 and header 18 is up to a predetermined temperature adequate to properly heat the air and raise the same to the desired evaporative capacity and furthermore until the humidity within the room or building served by my apparatus falls below a predetermined point causing the humidity control to close its switch or circuit control element.

Water delivered to the nozzle 13 is tempered or heated in its passage through tempering coil 26 and consequently will be more readily evaporated by the upwardly flowing air through flue 8. Nozzle 13 as heretofore 130

described, discharges a whirling conical spray of finely atomized particles of moisture. This conical spray strikes against deflection plate 17 and causes the moisture to be deflected substantially horizontally, transversely of the flue 8, emanating from the disk or plate 17 and being projected substantially radially from the center of said disk. The deflected finely divided spray fills the entire cross section of flue 8 at a plane disposed somewhat above the intake passages 8a and obviously all air traveling upwardly through the flue must pass through the said moisture or mist evaporating a very substantial portion of said moisture and of course carrying some unevaporated particles upwardly until the air passes through the reticulated portion of the radiator or heating unit. The heating unit raises the evaporative capacity of the air and quickly causes complete evaporation of any unevaporated particles present in the air at the time it strikes the fins and tubes of the radiator. The humidified air continues to travel upwardly through flue 8 into the discharge hood or cowl 9, which it will be noted extends horizontally across the top of ornamental casing C and diverges from the upper end of the flue. The height and other dimensions of the hood 9 are such that some small amount of pressure will be created in the hood causing an even distribution or discharge of the conditioned air from the several apertures of the grating 11.

In addition to being thoroughly and efficiently humidified the air in its travel through flue 8 is completely washed, since it must pass through the transverse spray or mist set up throughout the cross section of the flue between nozzle 13 and the cooperating deflector plate 17, and the air is also heated by the heating unit U.

As soon as the humidity of the air in the room or building is brought up to a predetermined point, the humidity control 34 opens the circuit through the coil of the solenoid valve and the valve element is seated, shutting off the supply of moisture to flue 8. Air of course will continue to travel through the flue and will be heated in so doing.

Any drops or particles of moisture which are not evaporated by the upward flow of air through the bottom of flue 8 will fall down upon screen 35, through which some air is circulated and some of this dropping moisture will be evaporated and any accumulation thereof will be removed from the device through the drain pipe 36. Screen 35 receives the dropping particles of moisture and prevents noise and sound which would be present if the particles dropped directly upon the metallic bottom of flue 8.

From the foregoing description it will be seen that I have invented a simple, comparatively inexpensive and highly efficient air

conditioning device having a high evaporative capacity, effected without the use of impellers and fans and provided with efficient controls connected in a circuit with a water supply valve in such a manner that moisture will not be distributed for humidifying the air until the radiator or heating unit is brought up to the proper temperature and until the humidity of the air in the room or building served by the device has fallen below a predetermined point.

It will of course be understood that various changes may be made in the form, details and proportions of the parts without departing from my invention, which generally stated, consists in the novel parts and combinations of parts and devices disclosed in the foregoing specifications and pointed out in the appended claims.

What is claimed is:

1. In air conditioning apparatus an upwardly extending flue having an air intake passage adjacent the lower end thereof and having a substantially horizontally disposed air discharge cowl diverging from the upper end of said flue, said air intake passage having a series of spaced divider plates adapted to cause entering air to be distributed substantially uniformly throughout the cross sectional area of the flue, a heating unit disposed transversely of the medial portion of the flue and having air passages extending therethrough, a water supply nozzle mounted adjacent said heating unit and directed longitudinally of said flue and a deflector plate associated with said discharge nozzle and adapted to deflect moisture transversely and substantially radially of said flue.

2. In air conditioning apparatus, an upwardly extending flue having an air intake passage adjacent its lower end and an air discharge passage adjacent its upper end, a nozzle disposed within said flue and directed downwardly longitudinally of said flue, said nozzle being connected with a source of water supply under pressure and adapted to discharge a finely divided spray of moisture, a deflecting plate mounted below said nozzle and axially aligned therewith for deflecting said spray transversely and radially throughout the cross sectional area of said flue and a heating unit having a core traversing the cross sectional area of said flue above said nozzle, said core comprising a multiplicity of very small heated passages extending longitudinally of said flue and adapted to entrain particles of moisture and vaporize and eliminate the same in the upward passage of the air.

3. The structure set forth in claim 2, wherein said passages are defined by straight, parallel walls extending longitudinally of said flue.

4. In air conditioning apparatus, an upwardly extending flue having an air intake

passage adjacent its lower end and an air discharge passage adjacent its upper end, a nozzle disposed within said flue and directed downwardly longitudinally of said flue, said nozzle being connected with a source of water supply under pressure and adapted to discharge a finely divided spray of moisture, a deflecting plate mounted below said nozzle and axially alined therewith for deflecting 10 said spray transversely and radially throughout the cross sectional area of said flue and a radiator having a core traversing a cross sectional area of said flue and disposed some distance above said nozzle, said 15 core being provided with a multiplicity of fins defining a multiplicity of straight, narrow passages extending longitudinally of said flue and adapted to entrain particles of moisture and vaporize and eliminate the 20 same in the upward passage of the air.

In testimony whereof I affix my signature.
CARROLL E. LEWIS.
